[57] CLAIM

The ornamental design for a battery-powered sharpener
for fish hooks or the like, as shown and described.

DESCRIPTION

FIG. 1 is a front elevational view of a battery powered
sharpener for fish hooks or the like showing my new
design;

FIG. 2 is a side elevational view thereof, the opposite
side being a mirror image;

FIG. 3 is a rear elevational view thereof;

FIG. 4 is a top plan view thereof;

FIG. 5 is a bottom plan view thereof.

Fig. 1.Fig. 2.Fig. 3.Fig. 4.Fig. 5.
